UNITED STATES PATENT OFFICE.

SAMUEL SOBEL, OF BROOKLYN, NEW YORK.

DESIGN FOR A PEDESTAL FOR DRESS FORMS OR SIMILAR ARTICLES.

Application filed August 5, 1926. Serial No. 18,603. Term of patent 3½ years.

To all whom it may concern:

Be it known that I, SAMUEL SOBEL, a citizen of Russia, residing at Brooklyn, in the county of Kings and State of New York, have invented a new, original, and ornamental Design for Pedestals for Dress Forms or Similar Articles, of which the following is a specification, reference being had to the accompanying drawing, forming part thereof.

In the drawing—

Figure 1 is a front elevation of a pedestal for dress forms or similar articles, showing my new design; and

I claim:

The ornamental design for a pedestal for dress forms or similar articles, as shown.

SAMUEL SOBEL.
